CASKET CONTAINER

Decio Torricelli, Springfield, Mass.

Application August 16, 1938, Serial No. 225,252

2 Claims. (Cl. 72—7)

My invention relates to improvements in casket containers and is directed more particularly to the provision of a burial vault for enclosing caskets of all kinds which is capable of easy assembly and which is more convenient to use than are the types of vaults heretofore used.

The principal objects of the invention are directed to the provision of a casket container which is adapted and arranged to be placed in a grave excavation in order to receive and contain therein a casket. According to the novel features of the invention, the burial vault is assembled from pre-cast cement members or sections which are secured together in a unique way so as to provide a unitary structure.

It has always been one objection of previous casket containers that they are too heavy and bulky and cannot be moved from place to place without a great deal of effort and trouble and it has been almost impossible for one man alone to carry such containers. According to my invention, I provide a container of the knock-down type which, as contrasted with the conventional container consisting of integral bottom, side and end walls and a top therefor, includes several separate pieces or sections which may be quickly and easily assembled or disassembled and which is, consequently, more easy to handle and more convenient to pack in compact form for shipping purposes. There is the further advantage that one man alone can assemble or disassemble the container. Furthermore, one man can even set the container up in an excavation without aid from anyone else which is a distinct advantage.

It is another object of my invention to provide an attractive container which accomplishes all of the purposes as set forth above and which still can be made more economically and with fewer operations in the manufacture of parts as well as in assembling than prior devices heretofore known in the art.

One very important feature in my invention is the provision of a container which is free from bolts and the like. No bolts are needed in the structure inasmuch as the container consists of interfitting parts which interlock by themselves without the aid of additional hardware of any kind.

Still another object is the provision of a device of the above character which consists of relatively simple parts adapted to be readily assembled, and when assembled to be positively and securely retained in operative relation. When as-

sembled, the parts cannot be readily separated from each other either accidentally or otherwise.

Various other novel features, advantages and objects of my invention will hereinafter more fully appear in the following description taken in connection with the accompanying drawing wherein:

Fig. 1 is a perspective view of a top end section;

Fig. 2 is a perspective view of a top intermediate section;

Fig. 3 is a perspective view of a side section;

Fig. 4 is a perspective view of an end section;

Fig. 5 is a perspective view of a bottom intermediate section;

Fig. 6 is a perspective view of a bottom end section;

Fig. 7 is a perspective view on a small scale of the various sections of the container in assembled position; and

Fig. 8 is a broken perspective view of a support for the container.

Like numerals refer to like parts in different figures in the drawing. Referring now to the drawing more in detail, the invention will be more fully described.

The various sections, some of which are shown in Figs 1 to 6 inclusive, are held in assembled relation, as will appear, by means of interfitting parts so as to provide a hollow container into which a casket may be inserted for burial purposes. While these various sections are preferably made of cement because of its durability, it will be understood that other materials could be substituted therefor without defeating the main purposes or objects of the invention.

In Figure 6, a bottom end section 10 is shown. This has generally flat upper and lower faces, but it is provided with an upstanding tongue 12 which extends transversely at one end upon its upper side.

Spaced inwardly of the marginal edges of the section 10 is a central raised portion 14 forming lips 17, 18 and 19 as shown.

The raised portion 14 is grooved longitudinally on opposite sides so as to provide tongues 16 and 18 as shown and by this arrangement a continuous groove around three sides of the raised section 14 and a lip on the fourth side is provided.

Another bottom end section, which is not shown, is similar to the bottom end section just described with the exception that a portion of the upraised portion, corresponding to 14 in Fig. 6, projects outwardly beyond the marginal edge 55

of the section so as to form a lip, for reasons as will hereinafter appear.

A bottom section 20 is shown in Fig. 5 which has generally flat upper and lower faces. An upraised portion 21 on the upper face is spaced inwardly of the marginal edges of the section so as to provide lips 23, 25, and 26 on three edges of the section. A part of the upraised portion 21 extends outwardly beyond the section 20 proper so as to provide a lip 22 as shown.

The upraised portion of the bottom section is also grooved longitudinally on opposite sides so as to provide tongues 24 and 24 as shown.

There may be any desired number of the sections 20 and there are two end sections 10 which constitute a bottom for the container. The said sections 10 and 20 are, in the assembling of the container, disposed adjacent one another with the tongues 16 and 16 and 24 and 24 in alignment so that said longitudinal grooves coincide so as to form continuous grooves. The lips 22 are adapted to overlap lips such as 19 and 23 all to the end that various sections fit tightly and snugly into each other.

To form a complete bottom wall for the container, the two end sections 10 are disposed in opposed relation with the desired number of bottom sections 20 therebetween. With such a feature, the length of the container obviously can be regulated as desired.

An end wall section is indicated by 30 in Fig. 4. This member includes an outer part of a certain width and height with an inner part of equal width but greater height. That is, the inner part projects above and below the outer part so as to provide lips 32 and 32 at the top and the bottom edges of the section.

Vertically extending grooves 34 are provided adjacent the opposite side edges of the said inner part of this section 30 and these grooves extend through the inner sides of the lips 32 as clearly shown.

There are two such end wall sections 32 which are substantially alike. In assembling, sections 30 are disposed vertically with respect to sections 10 with the lower lips 32 being seated in the grooves at the inside of lips 12. Furthermore, the grooves in part 14 of sections 10 are in alignment with the grooves 34 in sections 30.

One of a plurality of side sections 40 is shown in Fig. 3. While these may be unitary and of sufficient length to extend the entire length between the end walls when in working position, several smaller pieces may be used to form one section 40, if it is desired.

According to the preferred form of the invention, a plurality of sections 40 are disposed on top of one another to close up the side of the container. This is not necessary, however, inasmuch as a single section 40, if it is of sufficient height, may be used if it is so desired.

Each side wall member 40 has a longitudinal groove in its lower side between spaced parts 42. An upstanding tongue 44 extends longitudinally of the other side of the section 40. Provided on opposite ends of the section are vertical tongues 46 which are received in grooves 34 of the end sections 30 and tongues 16 and 24 of the bottom members are furthermore received in the grooves between the parts 42 of the lowermost side member.

In assembly, with the end and bottom walls associated as described, the sections 40 are disposed vertically above the bottom wall and between the end walls with the groove between

parts 42 thereof straddling the tongues 16 and 24 above mentioned, and as explained, the projections 46 will fit into the grooves 34 of the end walls.

Where there is more than one section 40 to a side, as shown in Fig. 7, the tongues 44 of the sections 40 will be received in the lower grooves between the parts 42 of the sections 40 directly above.

There may also be provided upon the outer faces of the sections 40 a notch or groove such as 48 which is adapted to facilitate manual engagement of the sections in carrying the sections from place to place. Obviously, such a feature may, if desired, be incorporated into all of the various members and sections so as to facilitate handling thereof in the same manner.

It will now be appreciated that with the side sections fitted together with the bottom and end wall sections an open container is formed. The means of closing this container will now be described.

One of two top end sections is indicated by 50 in Fig. 1 and is similar to one of the two bottom end sections. This section 50 has a transverse groove 52 adjacent its ends and longitudinal grooves (which are not shown) adjacent its opposite sides similar to the grooves in sections 10. The transverse groove 52 will receive the upper rib 32 of the end wall section 30, while the longitudinal groove will receive the tongue 44 of the uppermost side section 40.

Projecting inwardly from the upper side of the inner end of one end section 50 is a lip such as 54 while a similar lip projects inwardly from the lower side of the other end section.

A plurality of intermediate top wall sections are provided and one of these is shown as 60 in Fig. 2. These are similar to bottom wall sections 20 and have longitudinal grooves 62 adjacent opposite sides as well as lips 64 and 66 on opposite ends of the section as shown.

The said lip 54 of the one end section 50 overlaps the lip 66 of the adjacent top wall section 60 and the lip 64 of said adjacent section 60 overlaps the lip of the next adjacent section. The lip 64 of the last intermediate section 60 will, of course, overlap the said inwardly extending lip of the adjacent end section, all to the end that a closure member is provided thereby.

One modification of the invention may consist of a variation in the types of grooves and tongues which are provided as explained heretofore. For example, the grooves may be made deeper in their central portions than along their longitudinal edges. This may be accomplished by making the grooves concaved. The abutting tongues may likewise be curved so as to be substantially complementary to the form of the grooves in the interfitting sections.

If it is desired, a support 70 may be disposed underneath the completed container longitudinally thereof. Two or more may be disposed in spaced relationship under the container and these are used to facilitate in the handling of the assembled container if it is desired to move it as a unitary structure. Insets 72 may be provided at the opposite ends of the support which are adapted to receive straps, hooks or the like to enable the user to handle the container more easily.

When assembled a container is provided which has smooth surfaces on all sides both on the interior and the exterior.

When shipping or storing the sections, the same may be conveniently packed inasmuch as

the various top, bottom and end sections are of the same relative size and the side sections are of another convenient size.

While I have described the invention in great detail and with respect to the present preferred form thereof, it is not desired to be limited thereto since changes and modifications may be made therein without departing from the spirit and scope of the invention.

10 What it is desired to claim and secure by Letters Patent of the United States is:

1. A knock-down casket container comprising in combination, a horizontal bottom wall section formed to have an upstanding tongue at each of its opposite ends and a groove at the inner side of each tongue, said bottom wall section also being provided with a pair of longitudinally-extending tongues spaced inwardly from its side marginal edges, vertical side wall sections extending upwardly from the opposite sides of said bottom wall section and provided with tongues on their upper sides and grooves in their lower sides which receive the last-named tongues on the bottom wall section, vertical end wall sections extending upwardly from the opposite ends of said bottom wall section and provided with tongues on their upper sides and tongues on their lower sides which fit into said grooves in said bottom wall section, said end wall sections being provided with vertical grooves on their inner faces adjacent their side edges which receive opposite ends of said side wall sections, and a horizontal cover section provided with grooves in its lower side which receive said tongues on the upper sides of said end and side wall sections, all adapted and arranged whereby said sections are held in en-

gagement with each other in set up relation so as to form a hollow receptacle.

2. A knock-down casket container comprising in combination, a horizontal bottom wall including a plurality of adjacently-disposed sections, the outermost of said sections having an upstanding tongue at its outer end and a groove at the inner side of the tongue and all of said sections being provided with a pair of longitudinally-extending tongues spaced inwardly from their side marginal edges, vertical side walls extending upwardly from the opposite sides of said bottom wall, each side wall including a plurality of superposed sections and each section being provided with a tongue on its upper side and a groove in its lower side, the groove in the lowermost of the last-named sections receiving the last-named tongues on the bottom wall sections, vertical end walls extending upwardly from the opposite ends of said bottom wall and provided with tongues on their upper sides and tongues on their lower sides which fit into said grooves in said bottom wall, said end walls also being provided with vertical grooves on their inner faces adjacent their side edges which receive opposite ends of said side wall sections, and a horizontal cover including a plurality of adjacently-disposed sections, said sections being provided with grooves in its lower side which receive said tongues on the upper sides of said end and side wall sections, all adapted and arranged whereby said sections are held in engagement with each other in set up relation so as to form a hollow receptacle.
